UNITED STATES PATENT OFFICE.

HARRY D. ANDREWS, OF CHEYENNE, WYOMING.

HOOD ATTACHMENT.

Application filed April 14, 1922. Serial No. 552,757.

To all whom it may concern:

Be it known that I, HARRY D. ANDREWS, a citizen of the United States, residing at Cheyenne, in the county of Laramie and 5 State of Wyoming, have invented new and useful Improvements in Hood Attachments, of which the following is a specification.

This invention relates to attachments for 10 hoods of automobiles, and has for its object the provision of a device designed for engagement within the hinge knuckles of the upper leaves of an automobile hood subsequent to removal of the lower leaves, whereby to hold the hood properly in position.

It is well known that in hot weather a 15 great many automobile operators fold under the lower leaves of the hood so as to leave the sides of the hood open for greater ventilation to insure cooling of the motor it being customary either to allow the hood thus folded to rattle and jounce around or else to fasten the hood with a piece of hay wire or the like.

20 It is with these facts in view that I have designed the present device which includes bracket members pivotally engaged with the hinge knuckles of the upper leaves of the hood and having their lower ends formed 25 for engagement by the usual hood clips so that the hood will be properly held in position with the sides entirely open.

With the above and other objects and advantages in view, the invention consists in 30 the details of construction to be hereinafter more fully described and claimed, and illustrated in the accompanying drawings, in which:

Figure 1 is a side elevation of the front 35 portion of an automobile showing my device in position,

Figure 2 is a cross section through one side of the hood showing my device applied

40 Figure 3 is a perspective view of one of the bracket members detached,

Figure 4 is an elevation of the detached leaf of the hood.

Referring more particularly to the drawings the letter A designates the radiator of 45 an automobile, B designates the upper leaf of the hood which is formed at its lower edge with knuckles C pivotally connected, by the usual pintle rod D, with similar knuckles E formed at the upper edge of the 50 lower hood section or leaf F. The letter G designates one of the hood boards upon

which are mounted the clips H which are for the purpose of holding the hood down.

In carrying out my invention I remove the rod D at each side of the hood so that 60 the lower leaf section F may be entirely removed. I then make use of a pair of brackets 10 at each side of the hood. Each bracket is formed from a single length of 65 rod or heavy wire and has one end extended laterally as shown at 11 with its terminal formed with a hole 12. The other end of each bracket is laterally extended as shown at 13 and terminates in a finger 70 engaging loop 14.

The brackets are placed in position by inserting the lateral ends 11 through some of the knuckles C, after which cotter pins 15 are inserted through the holes 12 for preventing dislocation of the brackets. The 75 lateral portions 13 at the lower ends of the brackets are engaged beneath the hood clips H in exactly the same manner as the lower beaded edges of the lower hood sections or leaves are usually engaged. In this way it 80 will be seen that the brackets operate to hold the hood in position with the sides entirely open to permit free passage of air for insuring cooling of the motor.

While I have shown and described the 85 preferred embodiment of the invention, it is of course to be understood that I reserve the right to make such changes in the form, construction and arrangement of parts as will not depart from the spirit of the invention or the scope of the subjoined claims.

Having thus described my invention I claim:

1. Means for holding the upper leaves of 90 an automobile hood in position subsequent to the disengagement of the lower leaves therefrom, comprising a pair of bracket members detachably connected with the remaining upper leaves and formed for engagement by the usual hood clips, the upper 95 ends of the brackets being extended laterally and being pivotally engaged within the usual knuckles formed at the edges of the upper hood sections.

2. Means for holding the upper leaves of 100 an automobile hood in position subsequent to the disengagement of the lower leaves therefrom, comprising a pair of bracket members detachably connected with the remaining upper leaves and formed for engagement by the usual hood clips, the lower 105 ends of the brackets being laterally offset

2
for engagement by the hood clips and terminating in finger engaging loops.

3. Means for holding the upper sections of an automobile hood in position subsequent to the removal of the lower leaves from association therewith, comprising a pair of bracket members located at each side of the hood and each formed from a single length of rod having one end extending laterally

and pivotally engaged through the hinge 10 knuckles at the lower edges of the upper sections, the other end of each bracket being laterally extended for engagement beneath the hood clip and being coiled to define a finger engaging loop. 15

In testimony whereof I affix my signature.

HARRY D. ANDREWS.
